DISPLAY STAND FOR SUPPORTING STACKED CANDY BOXES

Amilcare Dogliotti, Neive (Cuneo), Italy, assignor to
P. Ferrero & C. S.p.A., Alba (Cuneo), Italy

Filed Oct. 1, 1969, Ser. No. 19,360

Claims priority, application Germany Apr. 19, 1969

Term of patent 14 years

Int. Cl. D6—01

U.S. Cl. D80—9

Fig. 1

FIG. 1 is a front elevational view of a display stand for supporting stacked candy boxes showing my new design; FIG. 2 is a bottom plan view thereof;

FIG. 3 is a top plan view thereof; and FIG. 4 is a perspective view thereof.

I claim:

The ornamental design for a display stand for supporting stacked candy boxes, as shown.
